UNITED STATES PATENT OFFICE.

ANNA M. DUTCHIER, OF ST. LOUIS, MISSOURI, ASSIGNOR TO LEWIS B. JONES,
OF SAME PLACE.

DESIGN FOR A PEDESTAL-LAMP.

SPECIFICATION forming part of Design No. 24,857, dated November 5, 1895.

Application filed May 3, 1894. Serial No. 509,991. Term of patent 14 years.

To all whom it may concern:

Be it known that I, ANNA M. DUTCHIER, a citizen of the United States, and a resident of the city of St. Louis, in the State of Missouri, have invented and produced a new and original Design for a Pedestal-Lamp, of which the following is a specification, reference being had to the accompanying drawing, forming a part thereof.

- o The drawing is a side elevation of a pedestal-lamp, showing my design.

The leading feature of my design consists of the circular base having an upwardly-curved portion surmounted by a dome-shaped portion having flutes or beading, the collar above the dome, the straight standard on which is located a beading, a globe-shaped portion, and the stem above the globe-shaped portion.

1 is the base, 2 is the upwardly-curved portion, and 3 the dome-shaped portion, having flutes or beading 4, of a pedestal-lamp. Over the dome is a collar 5, from which extends a straight standard 6, surmounted by a beading 7, a globe-shaped portion 8, a stem 9, and a ring 10.

Having thus described my invention, the following is what I claim as new therein and desire to secure by Design Letters Patent:

The design for a pedestal lamp substantially as herein shown and described.

ANNA M. DUTCHIER.

In presence of—

E. S. KNIGHT,
A. M. EBERSOLE.
